UNITED STATES PATENT OFFICE.

JAMES S. BROWN, OF THOMPSONVILLE, CONNECTICUT, ASSIGNOR TO THE HARTFORD CARPET CORPORATION, OF THOMPSONVILLE, CONNECTICUT, A CORPORATION OF CONNECTICUT.

DESIGN FOR CARPET OR RUG.

41,957.

Specification for Design.

Patented Dec. 5, 1911.

Application filed October 20, 1911. Serial No. 655,806. Term of patent 3½ years.

To all whom it may concern:

Be it known that I, JAMES S. BROWN, a citizen of the United States, and residing in Thompsonville, in the county of Hartford and State of Connecticut, have invented a new, original, and ornamental Design for a Carpet or Rug, of which the following is a specification, reference being had to the accompanying drawing, forming part thereof.

The figure is a face view of a carpet or rug showing my design.

I claim:

The ornamental design for a carpet or rug as shown.

JAMES S. BROWN.
